UNITED STATES PATENT OFFICE

ISAAC FISH, OF CLEVELAND, OHIO

COMB

Application filed April 21, 1930. Serial No. 445,916.

This invention relates to improvements in a comb and has for its principal object to provide for renewing broken teeth and to permit thorough cleaning without undue inconvenience. With the foregoing and other objects in view, the invention consists in the details of construction and arrangement of parts hereinafter fully described and claimed.

Fig. 1 is a side elevation with a portion broken away; Fig. 2 is a view looking at one edge and Fig. 3 is an exploded perspective view of an insert comprising end members, teeth and tie rod, only one of the teeth being shown.

Referring to the drawings, numeral 10 indicates the main body portion having substantially an I-shape, that is being provided with corner portions 10^a projecting from the main central portion. As is clearly shown in Figs. 1 and 2 the body portion 10 as well as the projections 10^a are hollowed out to receive an insert. This hollowing out takes the form of a U-shaped groove 11 formed in each side of the body portion 10 and extending around the notch or gap between the projections 10^a between which the teeth are seen in Fig. 1. Holes are drilled in each of the projections 10^a to receive screw threaded means 12 for holding the insert in the groove 11.

The insert, shown in Fig. 3 removed from the groove 11, comprises a pair of end members 13 adapted to slide into the groove 11 and provided with openings 14 to receive the threaded means 12 and openings 15 to receive a tie rod 16. Each of the members 13 is provided with a notch in one corner thereof in which the nuts 17 are received as well as the threaded projecting ends 16^a of the tie rod 16. Threaded on the tie rod 16 is a predetermined number of teeth 18 each of which consists of a body portion provided with an opening 18^a and a toothed portion 18^b. It will be observed that the toothed portion 18^b is somewhat narrower than the body portion of the tooth 18. This provides for the spacing of the teeth when they are threaded on the tie rod 16 in position of use.

From the foregoing it will be evident that

when one of the teeth 18 is broken, it is only necessary to disassemble the parts and insert a new tooth in place of the broken one. It is also evident that this comb can be thoroughly cleaned either by removing the tie rod 16 and cleaning each tooth separately or by simply removing the threaded means 12, slipping the insert of Fig. 3 out and rotating each tooth into accessible position whereby any dirt may be easily and thoroughly removed therefrom.

While I have shown a preferred embodiment of my invention I wish it understood that I am not limited to the details thereof but may carry out the same in a number of varying forms within the scope of the appended claims.

Having thus described my invention, what I claim is:

1. A comb including a body portion having a groove in one edge thereof, an insert received in said groove and detachably secured therein, said insert including a pair of end pieces and a plurality of teeth secured together by means of a tie rod upon which they are threaded.

2. A comb including a body portion having a groove in one edge thereof, an insert received in said groove and detachably secured therein, said insert including a pair of end pieces and a plurality of teeth secured together, said end pieces being provided with holes extending at substantially right angles to the length of said tie rod, holes in said body portion in alignment with said holes, and securing means extending through said holes for securing said insert in said groove.

3. A comb including a body portion having a groove in one edge thereof, an insert received in said groove and detachably secured therein, said insert including a pair of end pieces and a plurality of teeth secured together by means of a tie rod upon which they are threaded, said end pieces being provided with holes extending at substantially right angles to the length of said tie rod, holes in said body portion in alignment with said holes, and securing means extending through said holes for securing said insert in said groove.

4. A comb including a body portion having a groove in one edge thereof, an insert received in said groove and detachably secured therein, said insert including a pair of end pieces and a plurality of teeth secured together, one of said end pieces being provided with a notch into which an end of said tie rod extends.
5. A comb including a body portion having a groove in one edge thereof, an insert received in said groove and detachably secured therein, said insert including a pair of end pieces and a plurality of teeth secured together by means of a tie rod upon which they are threaded, one of said end pieces being provided with a notch into which an end of said tie rod extends.
6. A comb including a body portion having a groove in one edge thereof, an insert received in said groove and detachably secured therein, said insert including a pair of end pieces and a plurality of teeth secured together, said body portion having a plurality of corner extensions thereon, said groove extending into said extensions and being U-shaped, said end pieces being entirely received in said grooves.
7. A comb including a body portion having a groove in one edge thereof, an insert received in said groove and detachably secured therein, said insert including a pair of end pieces and a plurality of teeth secured together by means of a tie rod upon which they are threaded, one of said end pieces being provided with a notch into which an end of said tie rod extends, said body portion having a plurality of corner extensions thereon, said groove extending into said extensions and being U-shaped, said end pieces being entirely received in said grooves.

In testimony whereof, I hereunto affix my signature.

ISAAC FISH.
